HEMOSTATIC TONSILLECTOME

Oscar C. Daniels, Sr., Oriental, N. C.

Application February 24, 1949, Serial No. 78,127

7 Claims. (Cl. 128—309)

1

The type of surgical instrument to which my present invention is applied is a tonsillectome adapted for the use of physicians and surgeons in the excision of tonsils and it has for its object to improve the mounting for the knife or cutter in conjunction with the hemostat blade and also to improve the arrangement of the elements by means of which the two blades are successively advanced, first to hold a tonsil in a position separate from surrounding tissue and subsequently cause it to be severed.

Another object of my invention is to provide an improved retaining latch for limiting the retraction of the movable parts on the handle which also serves to yieldingly hold them in retracted position upon insertion of the instrument into the oral cavity of a patient and during the time the tonsil is being manipulated into the pillory.

To these and other ends my invention comprises further improvements and advantages as will be further described in the accompanying specification, the novel features thereof being set forth in the appended claims.

In the drawing:

Figure 1 is a perspective view of an instrument embodying my invention.

Figure 2 is a side elevation thereof.

Figure 3 is a rear elevation thereof.

Figure 4 is a top plan view of the instrument.

Figure 5 is an enlarged sectional view taken on the line 5—5 of Fig. 4.

Figure 6 is a view similar to Fig. 5 the hemostatic blade and knife blade being omitted.

Figure 7 is an enlarged cross sectional view of the pillory taken on the line 7—7 of Fig. 4.

Figure 8 is a side elevation of the hemostat blade showing one of its edge guides which also forms one of the guides for the knife blade.

Figure 9 is a top plan view thereof showing both of the double purpose guides.

Figure 10 is a fragmentary view showing the rear of the housing carried by the handle the blade operating parts having been removed therefrom.

Figure 11 is a side elevation of such blade operating parts removed from the handle.

Figure 12 is a vertical sectional view taken on the line 12—12 of Fig. 10 and showing the latch-retarder.

Figure 13 is a plan view of the knife and its manipulator.

Figure 14 is a side elevation thereof, and

Figure 15 is an end view of the manipulator.

2

Similar reference numerals, in the several figures, indicate similar parts.

The instrument illustrated is capable of being operated in either the right or left hand of the surgeon and comprises a frame 20 carried at its rear end on a handle 21, and of a length suitable to reach the sides of the throat when inserted in a patient's oral cavity while its outer end extends beyond the patient's lips for easy access in manipulating the movable parts carried thereon. The frame has an upper face 22 which is flat and extends from the rear end of the instrument, at a point above the handle to the fenestra, or circular opening 23 at its forward extremity into which a tonsil is manipulated. The inner end of the frame constitutes a pillory and is made as thin as possible, yet of sufficient substance to afford the requisite stability and provide the guides for the hemostat blade and the knife blade. As will be seen in Figs. 5 and 6 the end of the frame surrounding the aperture 23 forms a rim comprising a lower portion 24 and an upper portion 25 separated by a knife blade slot 26. The sides of the rim, indicated by 27, of this thickened end of the frame embrace the aperture 23 and extend in parallelism somewhat rearward of the opening 23, as shown in Fig. 4. The inner faces of these side portions 27 are undercut as indicated at 28 nearly to the point represented by the rear edge of opening 23 to provide guideways of greater width than said opening. The knife slot 26 extends into the guideways to accommodate a knife blade having a cutting edge which exceeds the diameter of the pillory opening 23.

The instrument frame is provided at its rear end with a housing 30 which serves as a retaining guide for the two blades of the instrument. The housing is formed integrally with the frame 20 and is supported at one side of the face 22, as indicated at 31 in Fig. 10, and curves over said face but terminates above the face to provide a slot 32 through which the instrument blades may be inserted and removed by a sidewise movement. At its forward end the housing has an interior semi-circular shoulder 33 and projecting inwardly at its rear end is a stop shoulder 34.

The movable parts of the instrument comprise a hemostatic blade and a cutting blade with means for operating the former quickly to engage a tonsil in the pillory and enucleate it and additional means for subsequently advancing the cutter, said parts being all carried on the hemostatic part of the instrument.

Figures 8 and 9 show in detail the forward or

pressure end of the hemostatic blade and Fig. 11 illustrates the operating parts carried thereon. It has a central arm 35 which is flat which lies parallel to the face 22 and is of the same width as the frame 20. At its forward end is a pressure plate 36 fitting between the sides 21 of the frame and rounded at its end to fit against the part 25. Pressure plate 36 has laterally projecting wings 37 fitting the guideways 28. The wings hold the forward end of the arm 35 elevated to support the pressure plate above the plane of the knife slot 26 in the frame and are slotted, as indicated at 38 in line with said slot. Extending forwardly from the guides is an element 39 which supports the underside of the knife blade. It is shaped like the hemostatic blade but is slightly narrower and not quite so long, as shown in dotted lines in Fig. 9.

At its rear end the arm 35 (see Fig. 11) terminates in a shoulder 40 and on its underside and forward of the shoulder is a circular projection 41 the face of which lies in the plane of the guide wings 37. It rides on the face 22 of the frame and maintains the arm 35 parallel thereto. On the arm 35, above the shoulder 40, is a boss 45 which aligns with the opening or aperture in the housing defined by the arcuate stop 33. A spindle 46a (shown in dotted lines in Fig. 11) is carried by boss 45, having one end rigidly secured thereto and its other end extending through the other elements and threaded to receive a locking nut which serves as a thumb pressure nut 52 and holds the elements against longitudinal movement with respect to blade 35. Spindle 46a slidably receives a second spindle 46 (Figs. 1 and 2) on which there is fixed a sleeve 47 of a diameter which neatly engages with an easy sliding fit within the housing 30, its inner end 48 being disposed to engage against the arcuate shoulder 33 in the housing at the time the pressure plate 36 contacts the inner portion of the rim 25 on the frame to prevent possible distortion of said rim. Entrance of the sleeve 47 into the housing in its proper operating position is provided by a longitudinal slot 49 cooperating with a guide 34. At about the mid point of the sleeve there leads a rearwardly extending spiral cam surface 50 designed to cooperate with the inner end of the guide 34 on the housing for forcing the arm 35 forwardly, this movement being initiated by rotary movement imparted to the sleeve by a butterfly or wing nut 51 fixed to the outer end of the spindle. The rotary movement is possible after the straight portion of the longitudinal slot (see Fig. 1) clears the guide 34 in the forward movement of sleeve 47.

The spindle 46 is threaded between nut 51 and sleeve 49 and rotatable on the thread is a pilot wheel 55 for advancing and retracting the cutter for which purpose it is provided with an annular recess 56.

An important object of my invention resides in the means for mounting the cutting blade and manipulating it in conjunction with the hemostatic blade whereby the parts may be readily disassembled for sterilization and with equal facility reassembled and new blades quickly inserted if needed between operations. I use as the cutter in this instrument a thin flexible steel blade having a head 60 rounded on its forward edge and having parallel lateral edges fitting in the guideways 38 in the wings 37 of the pressure plate 36. Extending rearwardly from the head 60 is a tail 61 of sufficient length to readily bend downwardly from said guides onto the face 22 of

the frame without interfering with the longitudinal movement of the head of the blade. The latter is advanced and retracted by a slide 62 to which it is connected by passing an aperture therein over a pin 63. Hooking these two parts together is facilitated by tapering the underside of the forward end of the slide upwardly so that it may be readily inserted beneath the end of the tongue 61 after the blade has been first inserted in the guideways 38. The slide 62, it will be observed, occupies the space between the frame face 22 and the underside of the arm 35 and is provided with a longitudinal slot 64 straddling the guide pin 41 on said arm. There is also a channel 63a in the face 22 of the frame to accommodate the pin 63. At its rear end slide 62 extends beyond the sleeve 47 on the spindle where it is provided with an upwardly extending flange 65 having a laterally opening slot 66 adapted to embrace the annular recess 56 on the hub of the pilot wheel. The slide 62 is thin enough to provide the required flexibility to allow it to readily slip over the pin 41 when its rear end is displaced sideways to engage the flange 65 with the pilot wheel and likewise to permit it to be sprung beneath said pin when the slide is disconnected from said wheel.

It is essential in an instrument of this character that it be capable of a one handed operation and because the frame when inserted in a patient's oral cavity is usually in a vertical position that the movable parts be frictionally held retracted. It is to these ends therefore that I provide at the rear end of the frame a spring operated latch that performs the dual functions of limiting the rearward movement of the two blades to set them in their initial operating position and also to frictionally retain them against accidental displacement during the manipulating of a tonsil from said wheel.

Directly above the handle 21 and beneath the housing 30 the frame is slotted, as indicated by 70 in Fig. 12, to accommodate a lever 71, pivoted at 72 and operated upwardly by a coil spring 73. Upward movement of the lever, when the blade elements are removed, is limited by a cross pin 74 which will engage the lip 75 on the frame. For retracting the lever its free end is provided with a thumb piece 76. On the upper edge of the lever 77 is a projection 77 which normally lies in the path of the end shoulder 40 on the arm 35 and limits the distance the hemostatic blade and the parts carried thereby can be retracted. This projection operates through the slot 64 in the blade operating slide 62 and when its forward edge engages the stop 40 its upper surface rests in engagement with the sleeve 47, the forward end of the latter being at this time within the housing 30. To provide the desired frictional contact at this time I taper the underside of the sleeve as indicated at 49a (Fig. 11) so that when the sleeve is pushed further into the housing 30 the latch is depressed against the tension of its spring 73.

In performing a tonsillectomy the patient is preferably in a prone position so that the distal end of the instrument when inserted in the mouth may be positioned with the hemostatic blade facing the tonsil which is to be removed and said end inserted between the tonsil and the posterior pillar for taking into the aperture 23 the lower pole or base of the tonsil. In this part of the operation it is possible to manipulate the shaft or instrument frame so as to permit an unobstructed view into the patient's throat and to lift the tonsil out of its bed in the sinus tonsilaris

causing it to pass into the pillory aperture 23 with possible manual aid applied to the tonsil. The above having been accomplished the application of pressure of the thumb upon the nut 52 will advance the hemostatic blade to dislodge the tonsil from its bed, the surgeon at this stage being careful to disengage any unwanted tissue. The advancing of the blade up to this point has positioned the cam 50 with reference to the stop shoulder 34 whereby turning of the wing nut will crowd the hemostat forwardly to crush the tonsil tissue to lessen bleeding but without actually severing it. The severing of the tissues is subsequently accomplished by advancing the knife blade 60 by rotation of the pilot wheel 55 on the threads of the spindle. It will be noticed that the rounded sharpened edge of the knife extends into the sides of the guide slot 26 and being wider than the hemostat blade cannot fail to completely sever all tissue engaged by said blade as the knife reaches the limit of its movement and passes beyond said blade.

Disassembling the instrument for cleaning and sterilization is extremely simple. Restoring the wing nut 51 disengages the cam 50 from the stop shoulder 34 and upon depressing the latch lever 70 the movable parts may be retracted to simultaneously retract the spindle sleeve 47 from the housing 30 and disengage the wings 37 on the hemostat blade from the undercut guideways 28, whereupon the connected blades may be dislodged from the frame by moving them laterally through the opening 32 at the side of the housing. Further separation of the two blades is accomplished by springing the slide 62 sufficiently to disengage the slot 64 from pin 41 and then swinging the flanged end 65 away from the pilot wheel. These parts being thus disconnected permits the withdrawal of the knife blade from the guide slots 38 and its disengagement from the pin 63 on said slide.

I claim:

1. In a tonsillectome, the combination with a frame for insertion in a patient's oral cavity having a flat upper face, the outer end of which is provided with an aperture, a rim surrounding the aperture and comprising side portions extending rearwardly thereof above said face, said rim being provided in its side portions with undercut guideways, of a hemostat blade fitting between the side portions of the rim, lateral wings thereon engaging said guideways and also having guideways therein below the hemostat blade, said hemostat blade having an arm for advancing and retracting the blade supported above the frame face, a knife blade supported in the last mentioned guides having a rearwardly extending flexible tail piece, a slide for advancing and retracting the knife lying between the arm and the frame and detachably connected to said tail piece and means at the outer end of the frame for manipulating said arm and slide longitudinally on the frame.

2. In a tonsillectome, the combination with a frame piece for insertion in a patient's oral cavity having a straight upper face provided at its distal end with an aperture and a rim extending above the face surrounding the outer side of the aperture and extending rearwardly of the aperture at each side thereof, said rim at its sides and adjacent said aperture being undercut to provide sets of guideways for a hemostat blade and a knife blade respectively, of a hemostat blade fitting within the rim, wings thereon engaging one of said sets of guideways, said wings and

hemostat blade also being slotted crosswise to provide guideways alined with the knife blade guideways in said rim, a flexible knife blade carried in the hemostat blade guides having a tail piece projecting rearwardly of the latter, an arm overlying the frame face attached to the hemostat blade, a slide member lying between the arm and frame and detachably connected to said tail piece and means at the outer end of the frame for manipulating said arm and slide lengthwise of the frame.

3. In a tonsillectome, the combination with a frame piece for insertion in the oral cavity having a straight face provided with a pillory aperture at its distal end, of a hollow housing on the proximal end of the frame, an inwardly extending stud on the housing, a hemostat blade and a knife blade guided for longitudinal movement on the frame across said aperture and extending at their rear ends beyond the housing, said knife blade being longitudinally movable relative to said hemostat blade the hemostat blade comprising an arm having a rotatable spindle extending through the housing, a sleeve on the spindle having a longitudinal slot to receive the housing stud to permit its insertion forwardly longitudinally in the housing and provided with a cam surface for engagement with the stud to advance the hemostat blade upon subsequent rotation of the spindle and a separate means for advancing and retracting the knife blade.

4. In a tonsillectome, the combination with a frame piece for insertion in the oral cavity having a straight face provided with a pillory aperture at its distal end, of a hollow housing on the proximal end of the frame supported at one side of its face and open at the opposite side of the frame, a hemostat blade and a knife blade carried thereon each comprising narrow arms insertable through the open side of the housing and guided on the frame for movement across said aperture, said knife blade being longitudinally movable relative to said hemostat blade an inwardly projecting stud on the housing, a spindle journaled on the hemostat arm, a sleeve thereon provided with a slot which permits the sleeve to be inserted in the housing and having a cam surface arranged to subsequently cooperate with the stud to advance the hemostat blade and separate means for advancing and retracting the knife blade.

5. In a tonsillectome, the combination with a frame piece for insertion in the oral cavity having a straight face provided with a pillory aperture at its distal end, of a hollow housing on the proximal end of the frame having an inwardly projecting stud at its rear portion, a hemostat blade comprising an arm overlying the face of the frame, a spindle on the arm concentric with the housing carrying a sleeve having a slot cooperating with the stud to initially position the sleeve in the housing, a cam surface leading away from one side of the slot and also cooperating with the stud to advance the hemostat arm and move its blade across the frame aperture upon rotation of the spindle, a knife blade carried by the hemostat blade and longitudinally movable relative thereto, independent means for advancing the knife, a spring operated latch mounted on a recess in the frame having a projection alined with the end of the hemostat arm to limit its rearward movement, and a finger trip on the latch overhanging the rear of the frame.

6. In a tonsillectome, the combination with a frame piece for insertion in the oral cavity having

a straight face provided with a pillory aperture at its distal end, of a hollow housing on the proximal end of the frame having an inwardly projecting stud at the top center of its rear end, a hemostat blade comprising an arm overlying the face of the frame, a spindle on the arm concentric with the housing carrying a sleeve having a slot cooperating with the stud to initially position the sleeve in the housing and also having a downwardly and rearwardly inclined surface on its under side, a cam surface leading away from one side of the slot and also cooperating with the stud to advance the hemostat arm and move its blade across the frame aperture upon rotation of the spindle, a knife blade carried by the hemostat blade and longitudinally movable relative thereto, independent means for advancing the knife, a spring operated latch mounted in a recess in the frame having a projection aligned with the end of the hemostat arm to limit its rearward movement and bearing upon said inclined surface to yieldingly resist forward movement of the hemostat arm and the parts carried thereby.

7. In a tonsillectome, the combination with a frame for insertion in an oral cavity having a straight upper face provided at its distal end with a pillory aperture and at its rear end with a downwardly extending handle and having a slot in said face opening at the rear side of the handle, of a hollow housing overhanging said face at its rear end having a stud projecting inwardly

from the housing, a hemostat blade having an arm overlying and spaced from said frame, a spindle on said arm concentric to the housing, a sleeve thereon having a longitudinal slot registering with the stud and a cam surface for also cooperating with the stud, said sleeve also having an inclined surface on its side which is undermost when its slot is initially engaged with the stud, a cutting blade carried on the hemostat blade and a slide for operating it located between the hemostat blade arm and the frame and having a longitudinal opening registering with the recess in the frame, a spring operated latch located in said recess and operating through the slide opening comprising a projection cooperating with the end of the hemostat arm to arrest its rearward movement and also bearing against the inclined surface of the sleeve to yieldingly restrain the forward movement of the arm and a thumb plate on the free end of the latch at the top of the handle for retracting the latch into an inoperative position.
